UNITED STATES PATENT OFFICE.

GARTH GRIFFITH GILPIN, OF RIVERSIDE, ILLINOIS.

UNCOUPLING LEVER FOR CAR COUPLINGS.

1,411,489.

Specification of Letters Patent. Patented Apr. 4, 1922.

Application filed August 10, 1915, Serial No. 44,717. Renewed August 27, 1921. Serial No. 496,126.

To all whom it may concern:

Be it known that I, GARTH GRIFFITH GILPIN, a citizen of the United States of America, residing at Riverside, in the county of Cook and State of Illinois, have invented certain new and useful Improvements in Uncoupling Levers for Car Couplings, of which the following is the specification.

10 The object of my invention is to provide between the hand lever and the lock pin lifter a joint which is flexible to service conditions, but which at the same time prevents the pin lifter from being rotated around 15 its axis, to such an extent at least as will make it possible for the pin lifter to be disengaged from the locking pin of the coupler, thereby, eliminating all danger of its becoming accidentally disengaged from the 20 coupler lock pin. A further object of my invention, is to provide a flexible joint between the hand lever and pin lifter of such construction that it is necessary to remove the hand lever from the car to disconnect 25 the lifter from the lever. A further object of my invention is to provide an uncoupling rigging wherein the hand lever and pin lifter may be assembled and shipped complete to assure their proper application to 30 the car; and with these and other objects in view, my invention consists of the parts and combination of parts, as will be herein-after pointed out.

In the drawings:

35 Figure 1 is a top plan view of a car, broken away, with my invention applied.

Figure 2 is an end elevation of a car showing my uncoupling lever in position.

40 Figure 3 is a top plan view of the hand lever.

Figure 4 is a front elevation of Figure 3, with the pin lifter added.

Figure 5 is a side elevation of the uncoupling lever and a coupler and associated parts.

45 Figure 6 is a similar view of the lever with the pin lifter in a different position from that shown in Figure 5.

Figure 7 is a side elevation of the pin lifter.

50 Figure 8 is a front elevation of the same.

Figure 9 is a detail top plan view of another embodiment of my invention.

Figure 10 is a front elevation and Figure 55 11 is a side elevation of Figure 9.

Figure 12 is a detail top plan view of another embodiment of my invention.

Figure 13 is a front elevation and Figure 14 is a side elevation of Figure 12.

The reference numeral 1 designates a car, 6 2 the end sill, 3 the dead wood or bumper and 4 a coupler of approved construction.

Brackets 5 and 6 are secured to the end sill in which is journalled the hand operated lever 7. The construction of these brackets 6 is such that the hand lever may be readily removed from the car. The lever 7 is provided at its inner end with a crank 8, which when the lever is mounted on the car, extends forwardly from the car over the 70 coupler. The outer end of the crank 8 terminates in a rectangular bearing, which in Figures 1, 2, 3, 4, 5, and 6, consists of an elongated eye 9, formed by rebending the outer end portion of the crank 8, the elongation extending in the direction of the length of the crank as shown in Figures 2 and 3. The crank at the outer end of the hand lever 7 is bent downward as at 10, as shown in Figures 2 and 4. 80

The lower end of the pin lifter 11 is formed into an open eye 12 and extended to form a helix. In applying the pin lifter to the hand lever the helical or cork screw end is passed through the eye 9 of hand lever 85

and the helical eye is then slightly closed, Figure 6 showing in dotted lines, the original position of the end of the hook and the full lines the partially closed position, so

90 that it cannot pass back through the eye of the hand lever, yet it can easily be passed through the eye of coupler lock block. This method has the advantage that the parts can be properly assembled at the factory. The

upper end of pin lifter 11 is bent to form 95 a hook 13 with an enlarged portion 14 to prevent it from slipping through the eye of the hand lever. That portion of the pin lifter which engages the eye of the hand lever is more or less rectangular, whereby it 100

slidably engages the eye of hand lever, but is prevented from rotating about an approximately vertical axis. With this arrangement it is impossible to remove the pin lifter from the eye of the coupler lock without removing the hand lever from the car. 105

In Figures 9, 10, 11, I show another embodiment of my invention, wherein the outer end portion of the crank 15 of the hand lever 16 is flattened and shouldered as at 17 and 110

30 and terminates in an upturned hook 18. The pin lifter 19 comprises a single bar or link terminating at the ends in hook 20 and eye 21. The hook 20 and a portion of the eye 21 are in the same plane while the outer end portion of the hook 21 is deflected from said plane as shown in Figure 11. The eye 20 is elongated as more clearly shown in Figure 10, to allow for upward movement 10 of the car coupler, due to the car passing over rough track, etc., also to allow the hand lever to return to normal position when the coupler is in lockset position. The shoulder 30 prevents the eye 20 from accidentally 15 binding on the crank 15. It will be noted that it is impossible for the pin lifter to rotate around its approximate vertical axis.

In Figures 12, 13, and 14, still another embodiment of my invention is illustrated. 20 In these figures 22 is the hand operated lever and 23 the forwardly extending crank at the inner end thereof. In this embodiment the elongated eye 24 is disposed transversely with respect to the crank 23. The pin lifter 25 has an upper flattened portion 26 adapted to pass through and work in the elongated eye 24, and terminates in a hook 27. It will be noted from figure 14 that the distance between the flattened portion 26 of the pin 25 lifter and the end of the hook is greater than the width of the eye 24 so that under all service conditions the hook is prevented from slipping through the eye 24, while also the flattened portion 26 is free to move trans- 30 versely of the eye to accommodate itself to service conditions, at the same time the pin lifter cannot rotate around its vertical axis. On the lower end of the link 25 is a hook 28 similar to the hook 21 shown in Figure 10. 40 With this construction it is not necessary to assemble the parts at the factory, and it is impossible for an ignorant workman to improperly apply the pin lifter to the hand lever.

45 When in service the pin lifter is normally in the position shown in Figure 5, the hook on the upper end of the lifter being slightly above the eye on the crank at the inner end of the hand lever, so that under draft the 50 coupler is free to move forward and the lower end of the lifter is free to move forward, the upper portion of the lifter being free to slide bodily in the eye until the upper hook engages the eye of said crank. Now 55 these parts are designed to permit of normal movements of the draw bar under buffing and draft strains, but should the movement of the draw bar be abnormal, as for instance when the draw bar breaks away from its 60 moorings, the engagement of the upper hook with the eye on the said crank will arrest the bodily movement of the pin lifter and thereby cause the lifter to pull the locking pin 29 of the coupler to unlocked position, 65 thereby uncoupling the coupler and break-

ing the trains which sets the brakes and stops the train, thereby preventing further damage.

While the pin lifter is free to move bodily to accommodate service movements of the 70 coupler, it is, by reason of the construction herein set forth, prevented from being rotated around a vertical axis whereby all danger of its becoming accidentally disengaged from the coupler lock or hand lever is 75 eliminated.

When the rigging has been bodily removed from the car, which is possible by removing the cotter pins and filler blocks from the brackets 5 and 6 (the brackets remaining 80 fixed to the car), the connection between the pin lifter and the pin is such that these parts can be disengaged free and without the removal of any part, such as a clevis pin, for example. On the other hand, with the device on the car, it is impossible to effect the disengagement of the coupler pin and pin lifter, either accidentally or intentionally. The theory is that if it could be intentionally disconnected, circumstances might arise 90 through accident which would bring about the disengagement unintentionally.

While for the purpose of illustrating my invention I have shown and described specific details of construction, I do not wish it 95 understood that my invention is thus limited, but changes may be made in the construction within the scope of the claims.

What I claim is:

1. The combination with a car and a resiliently mounted coupler having a lock pin provided with an eye; of a release rigging comprising a rod revolvably mounted on the car and having a crank provided with an elongated eye, and a link provided with a bent portion at its lower end extending through the eye of a lock pin and formed with a flattened shank extending non-rotatably but slidably through said elongated eye on the crank and provided with means 100 at its upper end for preventing its detachment from said crank.

2. The combination with a car and a resiliently mounted coupler having a lock pin provided with an eye; of a release rigging 115 comprising an operating rod revolvably mounted on the car provided with a crank having an eye, a link having a bent portion extending through the eye of the lock pin and a hook at its upper end extending through the eye of the crank and provided with enlarged head to prevent the disengagement of the link from the shaft, the eye on the crank and the portion of the link extending therethrough being shaped so that the link is slidably in the direction of its length through said eye but is in all positions non-rotatable with respect thereto. 120

3. The combination with a car and a resiliently mounted coupler having a lock pin 130

provided with an eye, of a release rigging comprising a rod revolvably mounted on the car having a crank, a link, means providing a connection between said crank and link which allows the link to move in the direction of its length with respect to the crank and angularly both forwardly and backwardly and sidewise, but prevents rotation of the link with respect to the crank in any position which the link may assume in service, said link being formed at its lower end with an open hook the end of which is curved out of the plane of the link and the part of the hook adjacent thereto and upwardly in a substantially spiral curve to a point on the other side of said link.

4. The combination with a railway car and a coupler resiliently mounted on the car having a locking pin provided with an eye; of a release rigging revolvably mounted on the car and provided with a crank, a link formed with a bent portion at its lower end to extend through the eye of the lock pin, and means providing a flexible undetachable connection between the crank and link, said connection comprising an eye on one of said members and a shank on the other extending slidably but non-rotatably through said eye to allow the link to move in the direction of its length with respect to the crank but without capacity for rotation at any position which the link may assume when attached to the lock pin.

5. In an uncoupling lever for car couplers, the combination with a horizontally rotatable rod secured to the end of a car, said rod having at its inner end a crank project-

ing outwardly over the coupler, a closed elongated eye, on said arm, a single link lifter connecting said crank and the lock pin of a coupler, said link having a flattened upper portion extending through said eye which normally extends a distance above and below the elongated eye to permit longitudinal movement without strain upon said crank, and having at its other end a hook which engages the eye of a lock pin, the joint between the link and elongated eye being flexible to permit of the link sliding in said eye but preventing it from rotating about a vertical axis; and means on the upper end of the link to prevent the link from becoming disengaged from the crank.

6. In an uncoupling lever for car couplers, the combination with an operating rod having an elongated eye on its inner end, of a pin lifter comprising a single member consisting of a round bar having a hook on its lower end deflected at an acute angle, the upper portion of said bar being flattened and terminating in a hook, and a knob on said last named hook of greater diameter than the said elongated eye; said flattened portion being adapted to pass through said elongated eye and form therewith a flexible joint which will not permit the said lifter to rotate about a vertical axis.

In testimony whereof I affix my signature in presence of two witnesses.
